UNITED STATES PATENT OFFICE.

JACOB N. COULBOURN, OF FEDERALSBURG, MARYLAND.

SCALDING APPARATUS.

1,213,843.

Specification of Letters Patent. Patented Jan. 30, 1917.

Application filed May 20, 1916. Serial No. 98,918.

To all whom it may concern:

Be it known that I, JACOB N. COULBOURN, a citizen of the United States, residing at Federalsburg, in the county of Caroline and State of Maryland, have invented certain new and useful Improvements in Scalding Apparatus, of which the following is a specification, reference being had to the accompanying drawings.

This invention relates to scalding apparatus and has relation more particularly to a device of this general character especially designed and adapted for use in canneries for scalding tomatoes or the like whereby the peeling of the tomatoes may be facilitated; and it is an object of the invention to provide a novel and improved apparatus of this general character wherein the tomatoes or the like to be scalded are first immersed and then caused to travel through a steam chamber.

Furthermore it is an object of the invention to provide an apparatus of this general character having novel and improved means whereby the water in which the tomatoes or the like are immersed is heated through the medium of the water or condensation within the steam chamber and through the medium of a spray which is heated by the action of the steam within the steam chamber.

The invention consists in the details of construction and in the combination and arrangement of the several parts of my improved scalding apparatus whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein—

Figure 1 is a view in side elevation illustrating a scalding apparatus constructed in accordance with an embodiment of my invention; Fig. 2 is an enlarged sectional view taken substantially on the line 2—2 of Fig. 1; with the sprocket chain omitted; Fig. 3 is an enlarged fragmentary view partly in elevation and partly in section illustrating the discharging end of the spray pipe as herein included; Fig. 4 is a longitudinal ver-

tical sectional view taken through the device as herein embodied, the water line within the tank being indicated by dot and dash; and Fig. 5 is a view in top plan of the device as herein disclosed.

As disclosed in the accompanying drawings, 1 denotes a tank of predetermined dimensions and having its upper face open, and in communication with the tank adjacent the bottom thereof is the pipe P leading from a suitable source of water supply and affording a means whereby the tank may be initially filled.

Extending upwardly within the tank 1 is an overflow pipe 2 having adjustably engaged with the upper end portion thereof the receiving head or member 3 whereby the water line within the tank 1 may be varied in accordance with the necessities of practice.

One end of the tank 1 has its upper portion reduced, as at 4, to afford communication with the receiving chute R disposed on a predetermined incline in a direction toward the tank 1 and in which baskets or other receptacles containing the tomatoes or the like to be scalded are initially positioned and which are adapted to be forced downwardly into the tank so that said receptacles and their contents will be immersed in the water within the tank 1. It is to be noted that the chute R is at such elevation as to have the water level within the tank to extend within the chute R to a point preferably immediately adjacent its outer end.

Supported by the tank 1 and overlying the top thereof at the end portion of the tank remote from the chute R, is a hood H provided with the hinged sides 5 whereby convenient access may be had therein. The inner end of the hood H is open but is normally closed by the depending flap 6 preferably of canvas and which is of such a length as to extend within the water contained in the tank 1, whereby said flap 6 serves to retain the heat entering within the hood H but readily permits an unobstructed passage of the baskets or receptacles in a manner which will hereinafter be more fully explained.

In communication with the outer end of the hood H and the adjacent portion of the tank 1, is the inclosed chamber or casing C of predetermined dimensions and disposed on an upward and forward incline, the outer end portion of which being supported in any conventional manner as indicated at 7.

The outer end of the chamber or casing C is open but is adapted to be closed by the depending flap 8 also preferably of canvas which serves to prevent the undue escape of steam discharged within the chamber or casing C and which also permits an unhindered discharge of the baskets or receptacles containing the tomatoes or the like.

Disposed transversely of the chamber or casing C adjacent the outer end thereof and in close proximity to the bottom of the casing or chamber C is a shaft 9 having affixed thereto at substantially the transverse center of the chamber or casing, the sprocket wheel 10 around which is disposed a sprocket chain 11 which extends inwardly of the chamber or casing C and is disposed around a sprocket wheel 12 rotatably supported by the end of the tank 1 remote from the chamber or casing and at a point below the receiving chute R so that the baskets discharged within the tank 1 from the receiving chute R will be operatively engaged by the upper stretch of the chain 11 and be carried thereby longitudinally of the tank 1 and through the chamber or casing C and discharged therefrom in a manner which is believed to be clearly apparent to those skilled in the art to which my invention appertains.

30 The baskets or receptacles are received directly upon the transversely disposed bars 14 suitably secured to the chain 11 and the bars 14 carried by the upper stretch of the chain have their extremities resting upon the guide 35 and supporting flanges 15 carried by the side walls of the chamber or casing C.

One end portion of the shaft 9 extends exteriorly of the casing or chamber C and has affixed thereto a sprocket wheel 16 around which is disposed a sprocket chain 17 which is also directed around a sprocket wheel 18 affixed to the shaft 19 rotatably supported by the casing or chamber C and disposed transversely thereof. As herein embodied, the shaft 19 is provided with a pulley 20 adapted to be coupled with a suitable source of power. The sprocket 18 is loosely mounted upon the shaft 19 but is provided with a clutch face 21 with which coacts the clutch member 22 slidably mounted upon the shaft 19 but rotating therewith. The clutch member 22 is adapted to be adjusted relative to the clutch face 21 in a conventional manner whereby it will be perceived that the shaft 9 may be caused to operate when the necessities of practice so demand.

Supported by the top of the casing or chamber C adjacent its outer or delivery end is a manifold M in communication with a suitable source of steam supply through the medium of the conduit 23, said conduit 23 having interposed therein a valve 24 whereby the supply of steam may be readily controlled.

65 In communication with the manifold M

are the pipes 25 preferably four in number and which extend within the casing or chamber C and are extended longitudinally thereof, and it is to be noted that two of the pipes are in vertical alinement and arranged adjacent the top and bottom of the chamber or casing C respectively, while the remaining two pipes are in horizontal alinement and arranged at the sides of the casing. The portions of the pipes 25 within the chamber or casing C are provided with the inwardly directed restricted openings 26 so that the steam admitted within said pipes will be discharged within the chamber or casing C in jets and in such a manner as to effectively engage the tomatoes or the like within the receptacles passing through the chamber or casing C so as to effectively scald said tomatoes in order to permit the same to be conveniently peeled after discharged from the chamber or casing C.

In communication with the casing or chamber C adjacent the discharge end thereof and through the top of said casing or chamber, is the flue F through which the steam within the casing or chamber C is adapted to be exhausted, and in order to facilitate the exhaust of said steam, I find it of advantage to arrange within said flue the steam jet 27 or the like for the purpose of creating a forced draft within the flue F.

Disposed longitudinally of the casing or chamber C and preferably in close proximity to the top thereof is a returned water pipe 28 having one end portion in communication with the pipe P at a point above or in advance of the valve 29 interposed in said pipe P for controlling the flow of water therethrough into the tank 1. It is to be understood that after the tank 1 has been initially filled, the valve 29 is adjusted into closed position. It will be observed that by having the supply pipe 28 disposed through the chamber C, the steam within said chamber serves to heat the water in the pipe before it passes to the tank.

The opposite end portion of the returned pipe 28 extends within the hood H and is provided with a plurality of depending branches or extensions 30 having their lower ends closed and their side or longitudinal walls provided with the restricted openings 31 through which the water is discharged in jets, whereby the water within the tank 1 is gradually replenished.

In order to agitate the water within the tank 1 to assure the proper circulation thereof, I position within the tank 1 the agitating blade 32 mounted upon an extremity of the shaft 33 extending exteriorly of the tank 1 and operatively engaged, as at 34, with the shaft 35 supported by the bracket 36 depending from the chamber or casing C and said shaft 35 is operatively engaged, as at 37, with the shaft 19.

Adjacent the manifold M each of the pipes 25 has interposed therein a controlling valve 38 whereby it will be perceived that the action of said pipes 25 may be independently controlled.

From the foregoing description, it is thought to be obvious that a scalding apparatus constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A scalding apparatus comprising a tank, an inclosed chamber in communication with the tank, a conveyer passing through the tank and the chamber, steam pipes leading from a suitable source of supply disposed longitudinally of the chamber and provided with inwardly directed openings, and a pipe leading from a source of water supply and disposed longitudinally through the chamber and extending above the tank and discharging therein.

2. A scalding apparatus comprising a tank, an inclosed chamber in communication with the tank, a conveyer passing through the tank and chamber, steam pipes leading from a suitable source of supply disposed longitudinally of the chamber and provided with inwardly directed openings, and a pipe leading from a source of water supply and

disposed longitudinally through the chamber and terminating above the tank and discharging therein, the portion of the last named pipe within the chamber being returned.

3. A scalding apparatus comprising a tank, an inclosed chamber in communication with the tank, a conveyer passing through the tank and chamber, steam pipes leading from a suitable source of supply disposed longitudinally of the chamber and provided with inwardly directed openings, a pipe leading from a source of water supply and disposed longitudinally through the chamber and terminating above the tank and discharging therein, the portion of the last named pipe within the chamber being returned, said pipe being also in communication with the tank adjacent the bottom thereof, and a valve for controlling the flow through said last named pipe.

4. A scalding apparatus comprising a tank, an inclosed chamber in communication with the tank, a conveyer passing through the tank and the chamber, steam pipes leading from a suitable source of supply and disposed longitudinally of the chamber and provided with inwardly directed openings, a pipe leading from a source of water supply and disposed longitudinally through the chamber and terminating above the tank, the portion of the last named pipe above the tank being provided with depending branches having their lower ends closed and their side walls provided with perforations.

In testimony whereof I hereunto affix my signature in the presence of two witnesses.

JACOB N. COULBOURN.

Witnesses:

O. MARTINE,
HARRY WHITE.
